BIOLOGICALLY TOXIC COMPOSITIONS CONTAINING BORON-PHENOL COMPLEXES AND METHODS

David R. Stern, Fullerton, and Friedrich J. Week, Hacienda Heights, Calif., assignors to American Potash & Chemical Corporation, Los Angeles, Calif., a corporation of Delaware

No Drawing. Filed Jan. 14, 1965, Ser. No. 425,609
12 Claims. (Cl. 167—30)

This is a continuation-in-part of application Serial Number 187,943, filed April 16, 1962, now abandoned.

This invention relates, in general, to biologically toxic compositions and to methods of combating biological growth. More specifically, the biologically toxic compositions comprise a major amount of inert matter and an effective amount of certain toxic ortho-substituted-phenol complexes.

Considerable difficulty has been experienced in trying to obtain broad protection against undesirable biological growth through the use of a single biological toxicant. The use of a single toxicant capable of inhibiting undesirable biological growth is highly desirable because it reduces the number of toxic ingredients required in biologically toxic compositions.

Further, previous biological toxicants have been limited in the scope of their usefulness because they were compatible or could be rendered compatible with only a limited number of substratum.

The term "substratum" as used in this specification and in the appended claims means any substance which it is desired to protect from undesired biological growth and which is capable of retaining on its surface or within itself, or both, a toxic amount of the biological toxicants which are more specifically described hereafter. The term includes liquids, powders, granular material, unitary solids, emulsions, solutions, dispersions, and heterogeneous systems such as a liquid-liquid, liquid-solid, or solid-solid type.

Broadly, the biologically toxic compositions according to this invention are comprised of a major proportion of (A) a substratum and (B) a toxic amount of an ortho-substituted-phenol complex. The ortho-substituted-phenol complex portion of these compositions comprises phenols having the formulas:

or

These phenol complexes may be used singly or in combinations of two or more.

In the above formulae, R can be any of the substituents, chlorine, fluorine, bromine, iodine, alkyl, cycloalkyl or aryl; R₁ can be any of chlorine, fluorine, bromine, iodine, alkyl, cycloalkyl or aryl, with the provision that only one of R and R₁ can be halogen on any given com-

2

ound; R₂ can be any of hydrogen, alkyl, cycloalkyl or aryl substituents; M can be any of the alkali metals, lithium, sodium, potassium, rubidium, or cesium; or ammonium. When one of R or R₁ is a halogen, the other can be an alkyl or cycloalkyl group containing from 4 to 24 carbon atoms or an aryl group containing from 6 to 24 carbon atoms. When neither R nor R₁ is a halogen, either one can be an alkyl group having from 2 to 22 carbon atoms, a cycloalkyl substituent having from 4 to 22 carbon atoms or an aryl group having from 6 to 22 carbon atoms, provided that there is a total of between 8 and 24 carbon atoms present in the two substituents combined. When R₂ is not hydrogen, it can be either an alkyl group containing from 1 to 7 carbon atoms, a cycloalkyl group containing from 4 to 7 carbon atoms or an aryl group containing from 6 to 10 carbon atoms. Thus, the total number of carbon atoms in the R and R₁ substituents combined is at least 4 when one of these substituents is halogen and at least 8 when neither R nor R₁ is halogen.

The method of inhibiting or substantially minimizing the growth of biological material on a substratum, comprises providing such substratum with an amount of the above described toxicants sufficient to render the resultant substratum-toxicant composite, toxic to biological material.

When the substratum is a finely divided solid or powder such as talc, clay, bentonite, or the like, the toxicant may be associated with it by, for example, mixing, blending, shaking, or by like means.

When the substratum is a liquid or an emulsion, the toxicant can be associated with it by dispersing, dissolving, or suspending the compound in the liquid or emulsion.

When the substratum is a unitary solid such as wood, fabric, fur, leather, organic plastic materials, or the like, the toxicant can be associated with it in many ways such as, for example, by dusting or spraying the toxicant onto the surface of the solid either with or without a solvent or diluent; or by soaking the unitary solid in a large body of liquid containing dissolved toxicant for a period of time sufficient to impregnate the solid with the desired concentration of toxicant; and the like. Pressure impregnation techniques also can be used, employing a pressure chamber in which the toxicant is introduced at elevated temperatures, either as a vapor or as a liquid entrained in another vapor such as toxicant-in-steam, and the like.

Hardenable coatings such as paints, enamels, varnishes, and like surface coatings can be associated with the toxicant by dispersing, grinding into, polymerizing or dissolving the toxic compounds in the fluid coating before the latter has hardened or by spraying or dusting the toxic compounds on the coating after it has been applied to a surface.

The substituents R, R₁ and R₂ of the ortho-substituted-phenol complex portion (B) of the composition, preferably are chosen so that the resulting toxicant is compatible with the desired substratum portion (A). Thus, if the substratum is water, R should be a low molecular weight substituent such as methyl, R₁ should be halogen or a low molecular weight alkyl and R₂ should be either hydrogen or a low molecular weight substituent such as methyl. If the substratum is a liquid hydrocarbon, R should be a large substituent such as octyl or nonyl, while the selection of R₁ and R₂ is not critical.

This invention is particularly useful in preventing the growth of undesirable biological matter in liquid hydrocarbons. There is a tendency for an aqueous phase to form in contact with a liquid hydrocarbon, due to ab-

sorption and condensation of atmospheric moisture. For this reason, during storage, liquid hydrocarbons are almost always in contact with an aqueous phase. Certain micro-organisms live in this aqueous phase and feed on the hydrocarbon. Thus, the interface between the aqueous and hydrocarbon phases is often covered with a growth of micro-organisms. An effective amount of toxicant dissolved in the hydrocarbon phase substantially inhibits the growth of these micro-organisms.

The term "normally liquid hydrocarbon" as used in the instant specification and in the appended claims includes gasoline, kerosene, naphtha, gas oil, cylinder stock, diesel fuel, jet fuel, heating oil, and the like. Normally, these hydrocarbons contain an average of from about four to fourteen carbon atoms, have a specific gravity or from about 0.6 to 0.95, an average molecular weight of from about 60 to 250, and an average boiling point of from about 40° F. to 700° F. "Average boiling point" is defined as the temperature of the boiling mixture of hydrocarbons when one half by weight of the hydrocarbons have been distilled off. In general, any hydrocarbon material from the lightest liquids through waxy solids to highly polymeric solids can be protected from attack by biological material, according to this invention.

This invention is also useful in preventing the growth of undesirable biological material on cellulosic substratum.

Cellulosic materials which can be provided with a toxic amount of the herein described toxicants, in accordance with this invention, include cellulosic films and filaments, fabrics, paper, wood, various compositions including wood in one form or another, such as compositions containing wood fibres in a matrix of some other material and the like. These cellulosic materials can be provided with a toxic amount of these compounds by any of the procedures described above, including particularly, impregnating as by soaking, treating the surface of the cellulosic materials, by spraying or dusting, and coating the surface with other compositions containing the toxic compounds such as varnishes, lacquers, calcimine, oil and water base paints, paper coatings of various kinds, and the like.

The preferred cellulosic material, according to this invention, is wood. Wooden articles provided with a toxic amount of the above described toxicants are extremely resistant to wood destroying fungus and insects. Many different types of wood can be protected in this manner. Thus, pine, fir, hickory, mahogany, oak, ash, spruce, birch, aspen, maple and the like, can be protected from insects and micro-organisms by providing them with a toxic amount of these compounds.

Wood can be provided with these compounds by any of the conventional, well-known procedures for impregnating woods with preservatives. These toxicants, which are boron complexes, can be introduced into the wood as complexes or the complex can be formed in situ in the wood by reaction between the corresponding ortho-alcohol-phenol and boric acid or some other soluble boron compound. This reaction can be accomplished, for example, by first impregnating the wood with one reactant, followed by a second impregnation with the other reactant. Various other agents can be employed with the toxicants, for example, surfactants which aid the penetration of the toxicant into the wood can be used.

According to this invention, the toxicants can be incorporated in wood in an amount ranging from about 0.1 percent by weight to about 0.05 percent by weight. It will be understood that the concentration of toxicant normally will be greatest at the surface of the wood and will decrease progressively with increasing depth into the wood. For this reason, the surface of the wood is often provided with an excess of toxicant so that the interior will contain an effective amount of the compound.

A further aspect of this invention comprises the provision of a toxic amount of the herein described toxicants with various substratum-surface coating compositions.

The toxicants can be incorporated in a substratum such as paint to render the paint resistant to the growth of biological materials. These paints find particular utility when applied below the water line on the hulls of sea-going vessels, where their anti-fouling properties are particularly valuable.

The paints, according to this invention, which can be provided with a toxic amount of toxicant are comprised primarily of pigment and vehicle.

The volatile constituents in the paint vehicle include, for example, hydrocarbons such as aliphatic and mineral spirit cuts, aromatics such as toluene and xylene, lacquer solvents, for example, esters such as butyl acetate, and ketones such as methyl ethyl ketone, mixtures of two or more vehicles, and the like. The non-volatile portions of the vehicle can include, for example, natural drying oils such as linseed oil, synthetic resins such as glycerol phthalate or phenol-formaldehyde, lacquers which dry by solvent evaporation such as nitrocellulose and other thermoplastic resins, materials such as silicones, mixtures of two or more non-volatile vehicles, and the like. The pigment portion of the paint can be either inorganic or organic, including, for example, chalk, cadmium yellow, bone black, azurite, litharge, mica, ochre yellow, pumice, white lead, zinc white, talc, red lead, silica, and the like. These pigments may be used singly or in mixtures of two or more.

The gloss of the particular paint is conveniently regulated by adjusting the proportion of pigment contained therein. In general, the lower the amount of pigment, provided it is present in a quantity sufficient to provide adequate covering, the glossier the paint.

According to this invention the toxicants can be incorporated in paint in an amount ranging from about 0.1 percent by weight to about 0.05 percent by weight. When these toxicants are used in anti-fouling marine paints to prevent the growth of various marine life on boat hulls, they are provided in relatively large amounts, for example, in excess of about 4 percent.

The biological toxicants used in the present invention are stable compounds which range from viscous liquids to crystalline or glassy solids. They are soluble in a wide range of solvents and as herein described, can advantageously be tailored to fit the solubility problems attendant the particular substratum involved. These ortho-substituted-phenol complexes can be advantageously employed for a variety of commercial and industrial purposes, but they are particularly useful as biological toxicants. When used as biological toxicants, they are effective at a concentration from as low as about one part per million parts of substratum up to a concentration of about 1,000 parts per million parts of substratum.

The ortho-alcohol-phenols used in the preparation of the toxicants used in this invention can be prepared conveniently by the reaction of a phenol having the formula:

65 with an aldehyde having the formula:

In the above formulas R , R_1 and R_2 have the values set forth above. This reaction is carried out in the presence of an alkaline catalyst. If an alkaline borate is used, the boron complex is produced. Treatment of the boron complex with acid will destroy the complex and produce the corresponding ortho-alcohol-phenol. This preparation is described in more detail in assignee's co-pending application Ser. No. 118,526, filed June 21, 1961.

Thus, when the reaction is carried out in the presence

of an alkaline borate, such as sodium borate, a novel boron complex forms substantially as follows:

The boron complex formed, as illustrated above, may be conveniently treated with a quantity of a dilute mineral acid to break the complex and release the compound of this invention. In carrying out these reactions, in addition to the sodium ion, the other alkali metals such as lithium, potassium, rubidium, and cesium may be used as well as the ammonium ion.

In the specification, claims and following specific examples, all parts and percentages are by weight unless otherwise indicated. The following examples are set forth to further illustrate and not to limit the invention:

Example I

This example illustrates the preparation of a toxicant additive: 2-chloro-4-tertiarybutyl-6-methylolphenol.

A solution of 50 gm. of sodium hydroxide (1.25 mols) and 62 gm. of boric acid (1 mol) in 500 ml. of water is added to 181 gm. of raw 2-chloro-4-tertiarybutylphenol (approximately 0.9 mol) and heated while vigorously stirring. When a temperature of 65° C. is reached, the addition of 100 ml. of a 36.1% aqueous solution of formaldehyde is begun. The initially milky mixture clears after about 20 minutes. The addition of formaldehyde is finished after two hours. After a third hour, the mixture turns cloudy and solidifies slowly while forming a soft crystalline mass. After standing overnight, the reaction mixture is repulped in 5 liters of cold water for the removal of the water-soluble components, and 205 gm. of a white, flaky material is obtained by vacuum filtration. After repulping in 600 ml. of benzene for the removal of the organic impurities, 95 gm. of a white crystalline material (borate complex) are obtained. The melting point is over 350° F. The crystals are tested for boron content by suspending one gram of the material in 30 ml. of benzene and contacting the suspension three times with 60 ml. of 0.1 N sulfuric acid, thus stripping the chelate of boron ions. The boron content of the aqueous phase is then determined by titration with alkali in the presence of mannitol (Scott's Standard Methods of Chemical Analysis I, 5th edition, New York, D. Van Nostrand Publishing Co., 1939, p. 170). Boron equivalent to 30.5 ml. 0.1 N boric acid is found in the aqueous phase, and indicates that the precipitate consists of a mixture of mono- and di-saligenin borate complexes, as can be concluded from the following calculations.

(a) The mono-saligenin borate complex:

One gm. of the above complex represents 0.0036 mol for which the boron content should be equivalent to 36 ml. of 0.1 N boric acid.

(b) The di-saligenin borate complex:

Na=C₂₂H₂₈O₄Cl₂Na₂B
Mol wt. = 459.153
Percent B, calculated = 2.35

One gm. of the di-saligenin complex corresponds to 0.0021 mol for which the boron content should be equivalent of 21 ml. of 0.1 N boric acid.

10 Since the titrated equivalent of the one gm. sample obtained by synthesis represents a value between these calculated figures, it can be concluded that the precipitate consists of a mixture of mono- and di-saligenin borate complexes. The estimated conversion of phenol to saligenin is 90%.

Example II

A water-hydrocarbon system is prepared using diesel fuel and sea water. The fuel has an average of 12 carbon atoms, a specific gravity of 0.85, an average molecular weight of 170, and an average boiling point of 500° F. The toxicant additive (the sodium salt of the boron complex of 2-chloro-4-nonyl-6-methylolphenol) is dissolved in the hydrocarbon to produce a solution containing 0.005% of the toxicant in the hydrocarbon. Water containing the fungus, Hormodendron, is introduced into the hydrocarbon.

After constant agitation for a period of 7 days at a temperature of 85° F., under the same conditions, a substantially identical water-hydrocarbon system containing no toxicant shows a substantial growth of micro-organisms while the solution containing the toxicant shows no discernible evidence of micro-organisms. The conditions of sea water and constant agitation used in this example, closely approximate those present in a ship at sea which contains fuel in storage.

Example III

Two specimens of pine wood (*Pinus radiata*, such as are found in Australia and New Zealand) measuring 3/4" x 3/4" x 18" are treated as follows:

The first specimen is impregnated by pressure injection with a saturated aqueous solution of the sodium salt of the boron complex of 2-butyl-4-butyl-6-(1-hydroxyethyl)-phenol. The second specimen is untreated.

The two specimens are inoculated with the fungus *Lensite trabea*.

The inoculated ends of the two specimens are buried in loose sandy soil to a depth of six inches and allowed to stand undisturbed. The specimens are then carefully removed from the soil and cleaned. The untreated specimen shows extensive deterioration while the treated specimen is substantially unchanged except for slight discoloration due to contact with the soil.

Example IV

55 A quantity of interior flat oil paint is prepared containing 65% pigment, 14% non-volatile vehicle, which is primarily treated drying oil, 21% turpentine solvent and 0.25% of the ammonium salt of the boron complex of 2-chloro-4-nonyl-6-methylolphenol.

60 A second quantity of paint having substantially the same composition except that it contains no 2-chloro-4-nonyl-6-methylolphenol complex, is prepared.

A line is drawn on a piece of 12 in. x 12 in. plywood so that it divides the surface into two halves, each measuring 6 in. x 12 in. One half of the plywood is given two coats of the complex-containing paint, while the other half is given two coats of the paint which contains no complex.

A culture medium is prepared containing the organism *Aspergillus niger* in a medium having the composition:

MgSO₄·7H₂O
NH₄NO₃
K₂HPO₄
KH₂PO₄
Sucrose and agar

The culture medium is seeded with spores of *Aspergillus niger* and incubated for 46 hours at 25° to 27° C., and 80 to 85% relative humidity, after which period of time the white mycelial stage of the mold is extended over the entire surface of the agar.

The painted plywood specimen is dipped in water and placed painted side down on the white mycelial growth so that half of the culture medium is in contact with the complex-containing paint and the other half of the culture medium is in contact with the paint which contains no complex. The whole specimen is further incubated while contact between the mold and painted surface is maintained.

The incubation is carried out at a temperature of 25° to 27° C., and 80% to 85% relative humidity for a period of 7 days. After this period of time, the control sample of paint, which contains no complex, shows substantial growth of dark sporulating mold growing on and in contact with the painted surface. The complex-containing paint shows substantially no evidence of dark sporulating mold either on or in contact with the painted surface.

Suitable inert carriers for use in this invention include, for example, finely divided talc, oil-in-water emulsions, mineral spirits, finely divided bentonite, benzene, diatomaceous earth, carbontetrachloride, water and an inert wetting agent, acetone and the like.

Satisfactory results are also obtainable by substituting any one or more of the following complexes in the above examples: the potassium salt of the boron complex of 2-chloro-4-(1,1,3,3-tetramethylbutyl) - 6-methylolphenol, the sodium salt of the boron complex of 2,4-di(tertiary-allyl)-6-methylolphenol, the lithium salt of the boron complex of 2-bromo-4-cumenyl-6-(1-hydroxyethyl)-phenol, the ammonium salt of the boron complex of 2-iodo-4-benzyl-6-(1-hydroxy-2-phenylethyl)-phenol, the rubidium salt of the boron complex of 2-fluoro-4-isoamyl-6-methylolphenol, the cesium salt of the boron complex of 2-nonyl-4-iodo-6-(1-hydroxyethyl)-phenol, the sodium salt of the boron complex of 2-methyl-4-pentadecyl-6-(1-hydroxy-2-cyclopentylethyl)-phenol, the ammonium salt of the boron complex of 2-cyclohexyl-4-cyclohexyl-6-methylolphenol, mixtures of two or more of these toxicants and the like. It will be understood that these boron complexes are generally present as a mixture of complexes having one and two substituted phenols per boron atom.

The organic substituents from which R, R₁ and R₂ can be selected can each be independently chosen from the following illustrative but not all inclusive list of organic substituents: alkyl substituents such as ethyl, methyl, isoamyl, neopentyl, decyl, hexyl, propyl, 2-methylpentyl, 5-methylhexyl, pentyl, dodecyl, butyl; cycloalkyl substituents such as cyclopentyl, cyclohexyl, cycloheptyl, p-methylcyclohexyl, 3-ethylcyclopentyl, 3,5-dimethylcyclopentyl, cyclobutyl; aryl substituents such as 2,4-xylyl, m-cumaryl, phenyl, mesityl, biphenyl, naphthyl, indanyl, tolyl and the like.

If R₂ is an organic group, preferably it will be an alkyl group having from 1 to 3 carbon atoms or a phenyl group. Organic substituents having more than these preferred limits of carbon atoms at this particular position, tend to provide more steric hindrance than is desirable for the formation of boron complexes or other reactions.

Preferred ortho-substituted-phenol complexes according to this invention, are those wherein R is an alkyl or cycloalkyl substituent having from 4 to 12 carbon atoms, R₁ is a halogen atom and R₂ is hydrogen or an alkyl substituent containing 1 to 3 carbon atoms. These preferred compounds are soluble in and compatible with a wide range of solvents and are very toxic to a wide range of biological materials.

The most preferred ortho-substituted-phenols are the boron complexes of 2-chloro-4-isoctyl-6-methylolphenol.

As indicated hereinabove, the biological toxicants can be contacted with the substratum in any one of several ways, for example, by mixing, dissolving, spraying and the like. Moreover, if desired, the toxicant can be associated with an inert carrier and the resultant composition can be contacted with the substratum. This inert carrier can be liquid, solid or gaseous. Thus, the toxicant can be dissolved or dispersed in a liquid inert carrier to form a toxicant-carrier composition which is then applied to a substratum. It will be understood that the toxicants can be prepared and supplied separate from or in combination with a carrier.

While the biological toxicants used in this invention are broadly toxic to all types of biological growth, they are particularly useful in combating micro-organisms and insects such as termites, mosquitos and moths. These toxicants find particular application in preventing mildew, for example, on leather and plastic goods. These toxicants are active against fungi, bacteria, algae and protozoa.

As will be understood by those skilled in the art, what has been described is the preferred embodiment of the invention. However, many modifications, changes, and substitutions can be made therein without departing from the scope and spirit of the following claims.

We claim:

1. A composition of matter comprising
(A) a major proportion of a substratum and
(B) a toxic amount of a compound selected from the group consisting of

(1) a compound having the formula:

(2) a compound having the formula:

and mixtures thereof, wherein

- (a) R and R₁ are each independently selected from the group consisting of halogen, alkyl, cycloalkyl and aryl substituents; one of said R and R₁ being halogen; the total number of carbon atoms in said R and R₁ substituents combined being from 4 to 24;
- (b) R₂ is selected from the group consisting of hydrogen, alkyl substituents containing from 1 to 7 carbon atoms, cycloalkyl substituents containing from 4 to 7 carbon atoms and aryl substituents containing from 6 to 10 atoms;
- (c) M is selected from the group consisting of alkali metal and ammonium.

2. A biologically toxic composition of matter comprising

(A) a major proportion of a finely divided solid and
(B) a toxic amount of a compound selected from the group consisting of

(1) a compound having the formula:

(2) a compound having the formula:

5

and mixtures thereof, wherein

- (a) R and R₁ are each independently selected from the group consisting of halogen, alkyl, cycloalkyl and aryl substituents; one of said R and R₁ being halogen; the total number of carbon atoms in said R and R₁ substituents combined being from 4 to 24;
- (b) R₂ is selected from the group consisting of hydrogen, alkyl substituents containing from 1 to 7 carbon atoms, cycloalkyl substituents containing from 4 to 7 carbon atoms and aryl substituents containing from 6 to 10 carbon atoms;
- (c) M is selected from the group consisting of alkali metal and ammonium.

3. A biologically toxic composition of matter comprising

- (A) a major proportion of a unitary solid and
- (B) a toxic amount of a compound selected from the group consisting of

(1) a compound having the formula:

10 and mixtures thereof, wherein

- (a) R and R₁ are each independently selected from the group consisting of halogen, alkyl, cycloalkyl and aryl substituents; one of said R and R₁ being halogen; the total number of carbon atoms in said R and R₁ substituents combined being from 4 to 24;
- (b) R₂ is selected from the group consisting of hydrogen, alkyl substituents containing from 1 to 7 carbon atoms, cycloalkyl substituents containing from 4 to 7 carbon atoms and aryl substituents containing from 6 to 10 carbon atoms;
- (c) M is selected from the group consisting of alkali metal and ammonium.

5. A biologically toxic composition of matter comprising

- (A) a major proportion of a liquid hydrocarbon and
- (B) a toxic amount of a compound selected from the group consisting of

(1) a compound having the formula:

25

(2) a compound having the formula:

30

and mixtures thereof, wherein

- (a) R and R₁ are each independently selected from the group consisting of halogen, alkyl, cycloalkyl and aryl substituents; one of said R and R₁ being halogen; the total number of carbon atoms in said R and R₁ substituents combined being from 4 to 24;
- (b) R₂ is selected from the group consisting of hydrogen, alkyl substituents containing from 1 to 7 carbon atoms, cycloalkyl substituents containing from 4 to 7 carbon atoms and aryl substituents containing from 6 to 10 carbon atoms;
- (c) M is selected from the group consisting of alkali metal and ammonium.

4. A biologically toxic composition of matter comprising

- (A) a major proportion of a liquid and
- (B) a toxic amount of a compound selected from the group consisting of

(1) a compound having the formula:

45

and mixtures thereof, wherein

- (a) R and R₁ are each independently selected from the group consisting of halogen, alkyl, cycloalkyl and aryl substituents; one of said R and R₁ being halogen; the total number of carbon atoms in said R and R₁ substituents combined being from 4 to 24;
- (b) R₂ is selected from the group consisting of hydrogen, alkyl substituents containing from 1 to 7 carbon atoms, cycloalkyl substituents containing from 4 to 7 carbon atoms and aryl substituents containing from 6 to 10 carbon atoms;
- (c) M is selected from the group consisting of alkali metal and ammonium.

6. A biologically toxic composition of matter comprising

- (A) a major proportion of a surface coating composition and
- (B) a toxic amount of a biologically toxic compound selected from the group consisting of

(1) a compound having the formula:

70

75

(2) a compound having the formula:

11

(2) a compound having the formula:

and mixtures thereof, wherein

(a) R and R₁ are each independently selected from the group consisting of halogen, alkyl, cycloalkyl and aryl substituents; one of said R and R₁ being halogen; the total number of carbon atoms in said R and R₁ substituents combined being from 4 to 24;

(b) R₂ is selected from the group consisting of hydrogen, alkyl substituents containing from 1 to 7 carbon atoms, cycloalkyl substituents containing from 4 to 7 carbon atoms and aryl substituents containing from 6 to 10 carbon atoms;

(c) M is selected from the group consisting of alkali metal and ammonium.

7. A biologically toxic composition of matter comprising

(A) a major proportion of a cellulosic substance and
(B) a toxic amount of a biologically toxic compound selected from the group consisting of

(1) a compound having the formula:

(2) a compound having the formula:

and mixtures thereof, wherein

(a) R and R₁ are each independently selected from the group consisting of halogen, alkyl, cycloalkyl and aryl substituents; one of said R and R₁ being halogen; the total number of carbon atoms in said R and R₁ substituents combined being from 4 to 24;

(b) R₂ is selected from the group consisting of hydrogen, alkyl substituents containing from 1 to 7 carbon atoms, cycloalkyl substituents containing from 4 to 7 carbon atoms and aryl substituents containing from 6 to 10 carbon atoms;

(c) M is selected from the group consisting of alkali metal and ammonium.

8. A biologically toxic composition of matter comprising

(A) a major proportion of an inert carrier and
(B) a toxic amount of a compound selected from the group consisting of

(1) a compound having the formula:

12

(2) a compound having the formula:

10

and mixtures thereof, wherein

(a) R and R₁ are each independently selected from the group consisting of halogen, alkyl, cycloalkyl and aryl substituents; one of said R and R₁ being halogen; the total number of carbon atoms in said R and R₁ substituents combined being from 4 to 24;

(b) R₂ is selected from the group consisting of hydrogen, alkyl substituents containing from 1 to 7 carbon atoms, cycloalkyl substituents containing from 4 to 7 carbon atoms and aryl substituents containing from 6 to 10 carbon atoms;

(c) M is selected from the group consisting of alkali metal and ammonium.

9. A method of combating the growth of biological material characterized by contacting said biological material with a toxic amount of a compound selected from the group consisting of

(1) a compound having the formula:

30

(2) a compound having the formula:

35

and mixtures thereof, wherein

(a) R and R₁ are each independently selected from the group consisting of halogen, alkyl, cycloalkyl and aryl substituents; one of said R and R₁ being halogen; the total number of carbon atoms in said R and R₁ substituents combined being from 4 to 24;

(b) R₂ is selected from the group consisting of hydrogen, alkyl substituents containing from 1 to 7 carbon atoms, cycloalkyl substituents containing from 4 to 7 carbon atoms and aryl substituents containing from 6 to 10 carbon atoms;

(c) M is selected from the group consisting of alkali metal and ammonium.

10. A method of substantially inhibiting the growth of biological material characterized by contracting said biological material with a composition comprising

(A) a major proportion of an inert carrier and
(B) a toxic amount of a compound selected from the group consisting of

(1) a compound having the formula:

70

75

13

(2) a compound having the formula:

and mixtures thereof, wherein

(a) R and R₁ are each independently selected from the group consisting of halogen, alkyl, cycloalkyl and aryl substituents; one of said R and R₁ being halogen; the total number of carbon atoms in said R and R₁ substituents combined being from 4 to 24;

(b) R₂ is selected from the group consisting of hydrogen, alkyl substituents containing from 1 to 7 carbon atoms, cycloalkyl substituents containing from 4 to 7 carbon atoms and aryl substituents containing from 6 to 10 carbon atoms;

(c) M is selected from the group consisting of alkali metal and ammonium.

11. A composition of matter comprising

(A) a major proportion of a substratum and
(B) a toxic amount of a compound having the formula:

14

12. A composition of matter comprising

(A) a major proportion of a substratum and
(B) a toxic amount of a compound having the formula:
